[57] CLAIM

The ornamental design for a growth chart photo album, as shown and described.

DESCRIPTION

FIG. 1 is a front view of the growth chart photo album fully extended, showing my new design for use as a photo wall chart;

FIG. 2 is a side view thereof;

FIG. 3 is a top view thereof;

FIG. 4 is a bottom view thereof;

FIG. 5 is a rear view thereof;

FIG. 6 is a perspective view thereof with the growth chart photo album partially folded;

FIG. 7 is a perspective view thereof with the growth chart photo album completely folded; and,

FIG. 8 is a another perspective view, showing the growth chart photo album folded and opened for use as a photo album.

FIGS. 1, 2, and 3 have been shown broken away for purposes of indicating indeterminate length.

1 Claim, 2 Drawing Sheets
